US0D1073857S

(12) **United States Design Patent** (10) Patent No.: **US D1,073,857 S**
(45) Date of Patent: ** May 6, 2025

(54) **MOBILE GAS STATION**

(71) Applicant: **CHONGQING LIDONG TECHNOLOGY CO.LTD.**, Chongqing (CN)

(72) Inventors: **ZhongBing Zhu**, Chongqing (CN); **Daoyong Chen**, Chongqing (CN); **Qiping Zhang**, Chongqing (CN); **Guolin Lu**, Chongqing (CN)

(73) Assignee: **CHONGQING LIDONG TECHNOLOGY CO. LTD.**

(**) Term: **15 Years**

(21) Appl. No.: **35/520,635**

(22) Filed: **Feb. 4, 2024**

(80) **Hague Agreement Data**

Int. Filing Date: **Feb. 4, 2024**

Int. Reg. No.: **DM/236511**

Int. Reg. Date: **Feb. 4, 2024**

Int. Reg. Pub. Date: **Apr. 26, 2024**

(51) **LOC (15) Cl.** **09-01**

(52) **U.S. Cl.**

USPC **D23/211.1**

(58) **Field of Classification Search**

USPC D23/202, 203, 204, 205, 211.1, 218;

Primary Examiner — Keith J Wilson

(57) **CLAIM**

The ornamental design for a mobile gas station as shown and described.

DESCRIPTION

The patent or application file contains at least one drawing executed in color. Copies of this patent or patent application publication with color drawing(s) will be provided by the Office upon request and payment of the necessary fee.

1. Mobile gas station

1.1 : Front

1.2 : Back

1.3 : Left

1.4 : Right

1.5 : Top

1.6 : Bottom

1.7 : Perspective

Used to add fuel to motor vehicles.
